E. L. RICHARDSON

HEATING SYSTEM

Filed Sept. 23, 1920

Inventor:
Ernest L. Richardson,
Albert G. Davis
His Attorney.

UNITED STATES PATENT OFFICE.

ERNEST L. RICHARDSON, OF LYNN, MASSACHUSETTS, ASSIGNEE TO GENERAL ELECTRIC COMPANY, A CORPORATION OF NEW YORK.

HEATING SYSTEM.

Application filed September 23, 1920. Serial No. 412,203.

To all whom it may concern:

Be it known that I, ERNEST L. RICHARDSON, a citizen of the United States, residing at Lynn, in the county of Essex, State of Massachusetts, have invented certain new and useful Improvements in Heating Systems, of which the following is a specification.

The present invention relates to heating systems wherein elastic fluid is taken from a heat engine after it has performed useful work therein and used for industrial purposes such as heating buildings, in manufacturing processes or the like. In such systems it is desirable to utilize the heat of the elastic fluid as completely as possible and the object of my invention is to provide an improved system for this purpose.

For a consideration of what I believe to be novel and my invention, attention is directed to the accompanying description and the claims appended thereto.

Referring to the drawing, 1 indicates a heat engine or prime mover, here shown as being an elastic fluid turbine having a supply conduit 2 and an exhaust conduit 3. Exhaust conduit 3 is connected by a pipe 4 to a condenser 5, there being two valves, 6 and 7 in pipe 4. Cooling water is supplied to condenser 5 by a pipe 8 in which is a valve 9, and is discharged therefrom to a pipe 10. Condensate is carried away from condenser 5 by a pipe 11 in which is a valve 12, pipe 11 leading to a conduit 13 which may convey the condensate to a hot well as is usual.

Leading from a point of intermediate pressure in the heat engine is a pipe 14 which connects to a second condenser or heater 15 and in pipe 14 are valves 16 and 17. Condensate from condenser 15 is conveyed by a pipe 18 provided with a valve 19 to conduit 13. Condenser 15 is connected in series with condenser 5 as regards the flow of cooling water, pipe 10 leading from the discharge of condenser 5 to the cooling water inlet of condenser 15 and being provided with a valve 20. From condenser or heater 15 the cooling water is led away by a pipe 21 which may convey it to any suitable point or points where it is to be used for industrial purposes. In pipe 21 is a valve 22.

Connecting exhaust pipe 4 to pipe 14 is a cross pipe 23 provided with a valve 24. Arranged around condenser 5 is a cooling water by-pass pipe 25 provided with a valve

26 and arranged around condenser 15 is a cooling water by-pass pipe 27 provided with a valve 28. Pipe 27 leads directly to pipe 21.

In normal operation valves 24, 26 and 28 are closed and the remaining valves are open. Exhaust steam from prime mover 1 passes through pipe 4 to condenser 5 and is there condensed giving up its heat to the cooling water entering the condenser through pipe 8. The condensate from condenser 5 is drawn off through pipe 11. The cooling water from condenser 5 passes through pipe 10 to condenser 15 where it is further heated by elastic fluid from an intermediate stage of the machine 1, the elastic fluid being supplied to condenser 15 by pipe 14. The elastic fluid from this intermediate stage is of course of higher temperature than the exhaust elastic fluid which is discharged through pipe 4 and in giving up its heat to the cooling water entering by pipe 10, such water is heated to a still higher temperature while the elastic fluid is condensed and is drawn off by way of pipes 18 and 13. The water after being heated in condenser 15 passes out through pipe 21 to a heating system where the heat is utilized.

It will be seen that by the above arrangement I first utilize the heat of the exhaust elastic fluid in heating the cooling water, which water is to be used in the heating system and I then provide the additional heat necessary to bring the water to the temperature desired by means of the second condenser or heater which takes elastic fluid from the heat engine at a higher temperature and pressure.

I thus utilize all the heat of the elastic fluid in the most economical manner, and at the same time give the engine the benefit of a low exhaust pressure which means a high efficiency.

By the piping arrangement shown I provide for various combinations for operation under special circumstances. By manipulating valves 6, 7, 16, 17 and 24 I may shut off either condenser 5 or 15 or connect either or both condensers to either or both of the pipes 4 and 14; and by means of the valves in pipes 8, 10, 11, 18, 21, 25 and 27 I may regulate the flow of cooling water and condensate to meet any special conditions under which the machine may be operating.

It will be understood that the devices 5 and 15 may be considered as being either or

dinary condensers, closed heaters, or heaters of any suitable type and by the term "condenser" as used in the specification, and claims, I intend to include any suitable forms of heat exchange apparatus such as is adapted for the purpose set forth.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. In combination, an elastic fluid turbine having an inlet conduit and an exhaust

conduit, a condenser connected to the exhaust conduit, a second condenser connected to the turbine at a point of intermediate pressure, conduits for conveying circulating water through said condensers in series, a heating system conduit to which the circulating water is delivered, means whereby the exhaust conduit may be connected to said second condenser.

2. In combination, a heat engine, two condensers connected thereto at points of different pressures, conduits for conveying cooling water through said condensers in series, and means whereby either condenser may be connected to either or both of said points of different pressures.

In witness whereof, I have hereunto set my hand this 21st day of September, 1920.

ERNEST L. RICHARDSON.
